UNITED STATES PATENT OFFICE.

LEONARD B. BUCHANAN, OF WOBURN, MASSACHUSETTS.

ELECTRIC FUSE.

1,281,285.

Specification of Letters Patent. Patented Oct. 15, 1918.

Application filed November 27, 1914, Serial No. 874,147. Renewed March 21, 1918. Serial No. 223,869.

To all whom it may concern:

Be it known that I, LEONARD B. BUCHANAN, a citizen of the United States, residing at Woburn, in the county of Middlesex and State of Massachusetts, have invented an Improvement in Electric Fuses, of which the following is a specification.

This invention relates to fuses and particularly to an indicator device adapted to show conspicuously and indicate from casual inspection whether the fuse is in operative condition or blown out. In devices of this character heretofore produced, it has been customary to provide an indicator member 10 visible at the outside of the fuse-holder and having controlling-means connected to the fuse-element at an intermediate portion thereof formed to localize the burning out action, in a manner so that when the fuse 15 burns out at this point, said visible indicator member is caused to be acted on by a spring or like means to push it out of a holder or otherwise change its position or appearance. This connection of said indicator member or 20 its controlling-means to the fuse-strip is, however, objectionable in certain particulars such as interfering with the convenient renewal of the fuse-strip after burning out and because it is otherwise desirable that the 25 fuse-strip be clear of hitch-ups with extraneous elements through its operative portion. The prime object of the present invention is, therefore, to provide an indicator-device for a fuse having means for conspicuously changing its position or appearance 30 and with its indicator-wire extending into the localized blow-out zone of the fuse-strip but free and clear of connection or engagement therewith adapted to be acted on 35 when the fuse blows out, so as to permit the indicator-device to operate. In accordance with my invention, the indicator-device is preferably formed as a self-contained entity adapted to be applied bodily to the fuse- 40 holder and to be located in proper proximity to the blow-out zone of the fuse-strip without actually contacting with the fuse-strip.

The foregoing, and other objects and features of the invention will be better understood from the following detailed description taken in connection with the accompanying drawings.

Referring to the drawings:

Figure 1 shows in side elevation and partial section, a fuse-holder and fuse with my

improved indicator-device embodied therewith.

Fig. 2 is an enlarged detail showing the indicator-device detached, and in position ready to be operated.

Fig. 3 is a similar detail showing the indicator-device after a blow-out has taken place, and,

Fig. 4 is an elevation of another form of indicator-device embodying this invention.

The fuse-holder 10 may be of the usual cylindrical type formed of insulating material having metallic end-caps 11, 12. The fuse-strip 13 extends between these end-caps, and at its central portion it is or may be reduced in cross-section, as at 14, to define the point at which the fuse will burn out and to constitute a localized blow-out zone. The fuse-strip may be supported by detachable mounts, such as are commonly employed in fuses having removable fuse-strips, or it may be supported by permanent mounts as is also now common. In the holder, toward one end thereof, I arrange the indicator-device of the present invention. The indicator-device, here shown, comprises a support, an indicator-member arranged on said support, actuating-means for said member also arranged on said support, an indicator-wire attached at one end to said member, and a bracket arranged on the support to which the other end of said wire is attached, said bracket being arranged to hold the end-portion of the indicator-wire in the blow-out zone of the fuse-strip. The support of the indicator-device may be arranged for permanent or detachable connection with the holder, and both forms of support are here shown. In Figs. 1 to 3, a support for permanent connection with the holder is shown, comprising a collar 15 set through a hole in the holder 10, and having a flanged head at its inner end, and having its outer end turned over upon the outside of the holder. In Fig. 4 a detachable form of support is shown, comprising a collar 25, with a flanged head at its inner end, and several bendable prongs 26, at its outer end, adapted to be bent over upon the outside of the holder. So far as my invention is concerned, the support, however, may be otherwise constructed, yet having the same capabilities. Adjacent the flanged head of the collar, a bracket or arm 16 is arranged, which extends in toward the center of the fuse and is bent down to a

point adjacent the reduced portion 14 of the fuse-strip, where it is formed with a hook 17, although said bracket may be otherwise arranged on said support. For connecting the bracket with the support it may have an aperture to embrace the collar and for security, said aperture may be of a size to snugly fit the collar. Fitted to the outside of the collar is a plate 18, which may be in the shape of a disk and colored so as to be conspicuously discernible, said disk serves as the indicator-member. A coil spring 19, which serves as the actuating-means for the disk-member, is housed in the collar and rests on the head thereof, having its outer end engaged with the disk-member. The disk-member and the spring engaged therewith are normally drawn down so that the disk-member rests on the top of the collar and the spring is under compression, by a fine flexible indicator-wire 20, which leads down through the collar and has its end soldered or otherwise suitably secured to the hook 17 of the bracket. The inner end-portion of the indicator-wire 20 is held by the bracket adjacent to, though wholly out of contact with the central-portion 14 of the fuse-strip. It will be observed that the indicator-device thus described constitutes a self-contained entity, the indicator-wire 20, holding the indicator-member normally down onto the top of its support, so that when its support is arranged in the holder, said indicator-member will occupy a position substantially flush with the outer surface of the holder without in any wise interfering with the fuse-strip or requiring any fitting thereto, and so that the fuse-strip may be inserted or renewed independently of the indicator-device. The indicator-device and the fuse-strip, though coöperating in use to indicate the blow-out of the fuse, are practically independent elements, adapted to be separately assembled with the fuse-holder. The essential feature of course, is the co-operative assemblage of elements, so that the inner end-portion of the indicator-wire will be supported close enough to the blow-out or arc-forming zone to be acted on sufficiently to rupture or release said wire upon the blowing out of the fuse. It is an advantage to enable the indicator-device to be mounted and held separate from and free of the fuse-strip, and I desire to protect this

feature irrespective of structural details, 55 hence the present embodiment is to be considered as illustrative and not restrictive.

Having described my invention, what I claim as new and desire to secure by Letters Patent is:—

1. An electric fuse, comprising a fuse-strip, a holder therefor, and an indicator-device supported wholly by said holder, said indicator-device consisting in an indicator-member, a spring for changing the position 65 of said indicator-member, an arm extending into the blow-out-zone, but free of said fuse-strip, and a flexible member for holding said spring normally inactive and connected to said arm in the blow out zone of the fuse- 70 strip, for the purpose stated.

2. An indicator-device for electric fuses made as a self-contained entity comprising a support arranged for detachable connection with the holder, an indicator-member and actuating means engaging said member and arranged on said support, a bracket also arranged on said support and an indicator-wire connected with the indicator-member at one end and with the bracket at the other 80 end, and adapted to be held by said bracket in the blow-out zone of the fuse-strip with the actuating-means in readiness to act upon the blowing of the fuse, substantially as described.

3. An indicator-device for electric fuses made as a self-contained entity comprising a collar having a flanged head at one end and prongs at the other end, whereby it may be detachably connected with the fuse-holder, 90 an indicator-member and actuating-means engaging said member and arranged on said collar, a bracket also arranged on said collar and an indicator-wire connected with the indicator-member at one end and with the bracket at the other end, and adapted to be held by said bracket in the blow-out zone of the fuse-strip with the actuating-means in readiness to act upon the blowing of the fuse, 95 substantially as described.

In testimony whereof, I have signed my name to this specification, in the presence of two subscribing witnesses:

LEONARD B. BUCHANAN.
